UNITED STATES PATENT OFFICE.

DAVID GOLDSMITH, OF NEWARK, NEW JERSEY.

TRUNK-FIXTURE.

No. 830,315.

Specification of Letters Patent.

Patented Sept. 4, 1906.

Application filed November 9, 1905. Serial No. 286,467.

To all whom it may concern:

Be it known that I, DAVID GOLDSMITH, a citizen of the United States, residing at Newark, in the county of Essex and State of New Jersey, have invented certain new and useful Improvements in Trunk-Fixtures; and I do hereby declare the following to be a full, clear, and exact description of the invention; such as will enable others skilled in the art to 5 which it appertains to make and use the same, reference being had to the accompanying drawings, and to figures of reference marked thereon, which form a part of this specification.

15 This invention has reference generally to improvements in attachments or fixtures for traveling-trunks; and the present invention relates more particularly to a novel means or fixture which is to be used with the one end 20 of what is known as a "wardrobe-trunk," the purpose of the device or fixture being to provide a means which will prevent the trunk being placed or stood upon its end, which is provided upon its inner face with a garment-hanger, said device or fixture serving at the 25 same time as a handle.

A further object of this invention is to provide a simple and cheaply-constructed device or fixture which while it serves the purposes above stated may also be used as a 30 handle for carrying this end of the trunk.

With these various objects of the invention in view my present invention consists, primarily, in the novel trunk-fixture herein- 35 after set forth; and, furthermore, this invention consists in the details of the construction of the device, all of which will be more fully described in the following specification and then finally embodied in the clauses of 40 the claim which are appended to and which form an essential part of this specification.

The invention is clearly illustrated in the accompanying drawings, in which—

Figure 1 is a view of a trunk placed upon 45 one end and a front elevation of the trunk-fixture applied to the other end of the trunk, said fixture embodying the principles of my present invention. Fig. 2 is a view of a portion of the end of a trunk-body and a plan or 50 top view of the trunk-fixture. Fig. 3 is an end view of the fixture and a sectional representation of the said end of the trunk-body, and Fig. 4 is a transverse section taken on line 55 5 5 in said Fig. 2. Fig. 5 is a plan view of a trunk-fixture of a slightly-modified form of construction, but still embodying the

principles of my present invention. Fig. 6 is a side view of the same; and Fig. 7 is a transverse section of the device, said section being taken on line 7 7 in said Fig. 5. 60

Similar characters of reference are employed in all of the said above-described views, to indicate corresponding parts.

Referring now to the several figures of the drawings, the reference character 1 indicates 65 any suitably-constructed trunk, and 2 is the flat end of the trunk-body or box with which the fixture or device embodying the principles of this invention is to be used. The said trunk-fixture is made of metal, and it comprises a main body 3, having at its respective ends downwardly-extending or angular end members 4, which terminate at their free ends in perforated securing ears or lugs 5. The said main body 3 is also provided with 70 suitably-disposed stiffening or side members 6, which extend laterally and downwardly from the said main body 3, preferably on opposite sides of the same, and terminate at their free ends in perforated securing lugs or 75 ears 7.

It will be clearly seen from an inspection of the drawings when the fixture is secured by means of rivets, pins, or the like, as 8, upon the outer face of the end 2 of the trunk 80 that while the device or fixture can be used as a handle for lifting or carrying the trunk it also serves the purposes of the ordinary bulge or enlargement now ordinarily used with wardrobe-trunks, the device making it 85 absolutely impossible to stand the trunk upon its end 2, as will be clearly understood from an inspection of Fig. 1 of the drawings.

In lieu of the form of trunk-fixture just described the said fixture may be made as 90 clearly indicated in Figs. 5, 6, and 7 of the drawings. In this construction the said main body 9 of the fixture and its downwardly-extending end portions or members 10 are made arc-shaped, as will be seen more 95 especially from an inspection of Fig. 6 of the drawings, the said body being concavo-convex in cross-section, as illustrated in Fig. 7, and the said end portions or members 10 each having a perforated lug or ear 11 for 100 the reception of pins or rivets 12. At suitable intervals the said curved body 9 is provided with laterally and downwardly extending and suitably-curved side members 13, having at their free ends perforated ears 105 or lugs 14, also for the reception of fastening pins or rivets 15, whereby the said fixture

can be secured in its operative position upon the end 2 of the trunk-body for the purposes previously stated. That the said main body portion 3 of the device shown in Figs. 1 to 4, 5 inclusive, may be used in the manner of a handle without cutting the hand said body 3 is preferably rounded off, as at 16. (See Fig. 4.) In like manner and for the same reason the body 9 of the device represented in 10 said Figs. 5 to 7, inclusive, is made with the rounded marginal edges 17, as clearly illustrated in said Fig. 7 of the drawings. The principal purpose of the said members 6 and 13 is to provide a stiffening or reinforcing 15 means for the main body of the fixture to prevent the fixture becoming broken during any rough handling of the trunk while in transit from one place to another. Furthermore, the main body of the fixture in either 20 case is sufficiently removed from the outer surface of the end of the trunk-body that it is an impossibility to place or stand the trunk on its end, which is of the greatest advantage in wardrobe-trunks, as will be 25 clearly evident.

Having thus described my invention, what I claim is—

1. A fixture for trunks to prevent the standing of the trunk on end, comprising a 30 rigid metal body, and laterally and downwardly extending rigid metal members connected with said body of the fixture, said members being provided with means for securing them upon the end of the trunk, 35 substantially as and for the purposes set forth.

2. A fixture for trunks to prevent the standing of the trunk on end, comprising a rigid metal body, end members extending 40 downwardly from the respective ends of said body, laterally and downwardly extending rigid metal side members also connected with the body of said fixture, and means connected with the various end and 45 side members for securing them upon the end of the trunk, substantially as and for the purposes set forth.

3. A fixture for trunks to prevent the standing of the trunk on end, comprising a 50 rigid metal body, laterally and downwardly extending rigid metal members connected with said body of the fixture, and perforated

ears at the lower and free ends of said members for attaching the fixture upon the end of the trunk, substantially as and for the 55 purposes set forth.

4. A fixture for trunks to prevent the standing of the trunk on end, comprising a rigid metal body, end members extending downwardly from the respective ends of said body, laterally and downwardly extending rigid metal side members also connected with said body of the fixture, and perforated ears at the lower and free ends of the various end and side members for securing 60 them upon the end of the trunk, substantially as and for the purposes set forth.

5. A fixture for trunks to prevent the standing of the trunk on end, comprising a rigid metal body, said body being made with 65 a rounded gripping-surface, laterally and downwardly extending rigid metal members connected with said body of the fixture, and perforated ears at the lower and free ends of said members for attaching the fixture upon 70 the end of the trunk, substantially as and for the purposes set forth.

6. A fixture for trunks to prevent the standing of the trunk on end, comprising a rigid metal body, said body being made with 75 a rounded gripping-surface, end members extending downwardly from the respective ends of said body, laterally and downwardly rigid metal extending side members also connected with said body of the fixture, and perforated ears at the lower and free ends of the various end and side members for securing 80 them upon the end of the trunk, substantially as and for the purposes set forth.

7. The combination, with an end of a 85 trunk, of a rigid metal fixture provided with downwardly-extending rigid metal members for securing said fixture upon the end of the trunk, said fixture being adapted to serve as a means to prevent the trunk being 90 stood upon end, substantially as and for the purposes set forth.

In testimony that I claim the invention set forth above I have hereunto set my hand this 6th day of November, 1905.

DAVID GOLDSMITH.
